UNITED STATES PATENT OFFICE

117,914

DESIGN FOR A TIRE CONSTRUCTION DISPLAY UNIT

George C. Van Veen, Chicago, Ill., assignor to
The Pharis Tire and Rubber Company, Newark,
Ohio, a corporation of Ohio

Application September 15, 1938, Serial No. 79,920

Term of patent 3½ years

To all whom it may concern:

Be it known that I, George C. Van Veen, a citizen of the United States, residing at Chicago, in the county of Cook and State of Illinois, have invented a new, original, and ornamental Design for a Tire Construction Display Unit, of which the following is a specification, reference being had to the accompanying drawing, forming a part thereof.

Fig. 1 is a perspective view of the tire construction display unit showing my new design;

Fig. 2 is a top plan view thereof;

Fig. 3 is a side elevational view.

The dominant features of the design are shown in full lines on the drawing.

I claim:

The ornamental design for a tire construction display unit, as shown and described.

GEORGE C. VAN VEEN.
